(57) **CLAIM**

The ornamental design for a vehicle mountable lighted warning sign device, as shown and described.

DESCRIPTION

FIG. 1 is a front elevational view of a vehicle mountable lighted warning sign device showing my new design;

FIG. 2 is a rear elevational view of the vehicle mountable lighted warning sign device;

FIG. 3 is a side elevational view of the vehicle mountable lighted warning sign device;

FIG. 4 is a top plan view of the vehicle mountable lighted warning sign device;

FIG. 5 is a bottom plan view of the vehicle mountable lighted warning sign device; and,

FIG. 6 is a front perspective view of the vehicle mountable lighted warning sign device.

The word indicia in broken lines are for example purposes only and form no part of the claimed invention.
